UNITED STATES PATENT OFFICE.

PAUL EUGÈNE GASTON SWYNGHEDAUW, OF CHARENTON, FRANCE.

MACHINE FOR BREAKING, SOFTENING, AND SCUTCHING FIBROUS STOCK.

1,341,603.

Specification of Letters Patent.

Patented May 25, 1920.

Application filed August 22, 1919. Serial No. 319,220.

To all whom it may concern:

Be it known that I, PAUL EUGÈNE GASTON SWYNGHEDAUW, a citizen of the Republic of France, and a resident of 7 Rue Pasteur, Charenton, Department of Seine, France, have invented new and useful Improvements in Machines for Breaking, Softening, and Scutching Fibrous Stock, of which the following is a specification.

10 This invention relates to a machine intended to break, soften and scutch fibrous stock, more particularly flax and hemp, retted or not retted, and any other fibrous stock in stalks, as well as to soften the tow 15 of hemp, ramie, etc.

The invention relates more particularly to a machine in which the textile material to be treated, advances in a layer between cylinders provided with blades, and having 20 a movement of rotation about parallel axes, and a table having a surface parallel to the plane of rolling of the said blades and provided in its turn with several fixed blades with the same spacing as that between the 25 blades of the rotary cylinders; the fibrous stock is thus broken between the blades of the cylinders and the blades of the table.

An apron constituted by bars arranged 30 parallel to the generatrices of the rotary cylinders and supported at their ends by endless chains, at a distance apart corresponding to the distance between the axes of the said rotary cylinders, has a continuous advance movement between the cylinders and the blades of the table, behind the layer of fibrous stock, so that the said bars push in front of them the material and disengage it from the blades or teeth of the table, after it has been treated by the passage 35 of one of the rotary cylinders, in order to be treated again by the passage of the next cylinder in front of the table.

The accompanying sheet of drawings shows, by way of example, a construction in 40 which the cylinders with blades are mounted on a drum which has a rotary movement and brings about the movement of rotation of the said cylinders about their axes, as well as the drawing of the endless chains 45 supporting the bars of the apron.

Figure 1 is a vertical axial section through the apparatus, Fig. 2 is a similar view showing diagrammatically the method of driving of the endless chains of the apron, Fig. 3 is 50 a partial side elevation, Fig. 4 is a side

elevation showing a clutch or coupling device by means of which the direction of running of the cylinders distributing the fibrous stock can be reversed and thus the said material be withdrawn and disengaged 60 after it has been treated on one of its faces.

The apparatus comprises a series, of any desired number, of fluted or grooved cylinders *a* mounted on spindles *a*¹ supported at their ends by disks *b*; the latter are mounted 65 on a spindle *b*¹ supported by the frame *c*. The spindles *a*¹ of the cylinders *a* are all arranged at the same radial distance from the spindle *b*¹, and at equal distance from each other. The teeth of the grooved cylinders *a* are constituted by blades *d* extending 70 throughout the whole length of the said cylinders. Outside the end disks *b*, and concentrically with the same, is arranged a toothed rim *b*² secured to the frame and 75 meshing with toothed pinions *a*² secured to the grooved cylinders *a*, the pitch circle of the toothed pinions *a*², is tangent to the pitch circle of the toothed rim *b*². The teeth of the grooved cylinders *a* have for 80 their pitch circle that of the pinions *a*².

When a movement of rotation is imparted in any suitable manner to the spindle *b*¹ which carries the disks *b* with the grooved cylinders *a*, the latter will be given a movement 85 of advance and at the same time, owing to the engagement of the toothed pinions *a*² secured to the spindles *a*¹, with the rim *b*² with inner teeth, secured to the frame, they will be given a movement of 90 rotation about the spindles *a*¹.

Opposite the plane of rolling of the teeth *d* of the grooved cylinders, and parallel to the said plane, is mounted a grooved table *e* comprising a series of blades *e*¹ 95 spaced to the same extent as the blades *d* which form the teeth of the grooved cylinders. These blades *e*¹ are arranged parallel to the generatrices of the cylinders *a* and radially relatively to the spindle *b*¹ as 100 center.

The table *e* is provided at its two ends with lugs *f* secured to each other; these lugs are not secured to the frame *c* of the machine, but simply supported by the latter; they are 105 held in place by rods *g* pivoted at *g*¹ to the lugs and guided at *h*¹ in guides *h* secured to the frame; the end of each rod rests on the arm *i* of the lever *i*¹ pivoted at *i*²; this arm *i*¹ is held by a spring *i*³.

Under the action of the said springs i^3 , the table $e e^1$ strikes stops j which thus limit the position of the table relatively to the grooved cylinders a . This arrangement 5 makes possible a movement back of the table in the event of a fibrous stock of excessive thickness being introduced, and thus avoids any breaking of the material and damage to the machine.

10 The fibrous stock to be treated (flax, hemp, ramie etc.) driven by an endless band or a table k and feed rollers k^1 arranged in front of the table k , arrive in a layer on the grooved table e . Owing to the movement of 15 rotation of the grooved cylinders a , combined with the movement of rotation of the disks b carrying the said cylinders a , the latter pass successively in front of the table $e e^1$, the blades d of the cylinders a engaging 20 with the blades e^1 of the table. The material brought to the table is thus broken. In order to disengage the material gripped between the blades or teeth e^1 of the table, I use an endless apron, (Figs. 2 and 3) comprising 25 two chains m (one at each side of the frame) connected together by bars n of wood or of metal, of U-shaped cross-section or simply rectangular; these bars which are parallel to the generatrices of the grooved cylinders a , are arranged at a distance apart, equal to the length of the arc of circle comprised 30 between the spindles a^1 of two adjoining cylinders a .

The chains m are supported by rollers m^1 , 35 guided between the lower feed roller k^1 and the upper part of the grooved table e by a guide e^2 , so that they rest against the disks b , the rims of which are provided with teeth b^3 of the pitch corresponding to that of the 40 chain, so as to drive the latter at the same speed of advance as the cylinders a during the rotation of the said disks about the spindle b^1 ; the chains m leave the disks in order to pass over rollers m^2 , the position of 45 which is adjustable, and rise toward the roller m^1 . A bar n of the apron arrives at the upper part of the table and engages between the disks b at equal distance from two cylinders a . It pushes in front of it 50 the fibrous stock and in passing in front of the grooved table $e e^1$ disengages all the material engaged between the blades or teeth e^1 of the grooved table and shakes it so as to bring it again under the action of the 55 blades of the next rotary cylinder during its passage in front of the grooved table. To each bar of the apron corresponds a bar o of wood or metal, movable about a spindle p supported by the disks b . The 60 crushed material is thus scraped between the bars n and the bars o , the distance apart of which is adjustable at will. This scraping brings about the removal of shive from the material.

65 The machine is provided with a double

clutch enabling the direction of running of the feed rollers $k^1 k^1$ to be reversed and consequently the fibrous stock treated between the grooved cylinders $a d$ and the grooved table $e e^1$, to be withdrawn and disengaged. 70 To that end, on the spindle k^2 of one of the feed rollers k^1 (Fig. 4) are mounted loose two claw coupling sleeves r and s secured respectively to the toothed pinions r^1 and s^1 ; the latter mesh with toothed pinions respectively r^2 and s^2 secured to countershaft pulleys r^3 and s^3 mounted on a countershaft k^3 ; these pulleys are driven respectively by an open belt and by a crossed belt r^4 and s^4 from one and the same spindle k^4 , so as to 80 have a movement of rotation of the same speed, but in opposite direction to each other.

A clutch sleeve t operated by a bifurcated lever t^1 , is mounted by means of a long spline 85 at t^2 on the spindle k^2 of the feed rollers k^1 , so that it can be brought into engagement with one or the other of the claw sleeves r and s ; according to circumstances, the feed roller k^1 will thus be given a movement of 90 rotation resulting in the introduction of the fibrous stock between the blades $d e^1$ or in a withdrawal of the said material from the said blades. This retrograde movement of the fibrous stock produces a very energetic 95 action of the grooved cylinders $a d$ and of the scraper bars o , in coöperation with the blades of the table e , and has the advantage (more particularly in the case of flax) of maintaining the feet of the stalk or fibers 100 at the same level and of giving what is known in the trade under the name of well scraped flax.

When the fibrous stock has been thoroughly treated on one of its faces, it is withdrawn from the machine by operating the clutch or disengaging lever f^1 ; it is turned over and treated on the other face by introducing it again into the machine between the feed rollers k^1, k^1 , which are caused to 110 rotate in the opposite direction by pushing the clutch lever t^1 in the opposite direction.

What I claim is:

1. A machine for breaking, softening and scutching fibrous stock, comprising cylinders rotatably mounted about parallel axes, means for rotating said cylinders, blades arranged along the generatrices of said cylinders, a table having a surface parallel to the plane of rolling of said blades, fixed blades on said table with the same spacing as that of the blades of the rotary cylinders, means for feeding the fibrous stock to be treated between the blades of the rotary cylinders and the blades of the table, and means for disengaging the treated fibrous stock from the blades of the table as it advances. 125

2. A machine for breaking, softening and scutching fibrous stock, comprising cylinder 130

for giving to the said apron a continuous advance movement between the cylinders and the blades of the table, at the same linear speed as the drum carrying the rotary cylinders, for the purpose described, during the bodily rotation of the said drum and the planetary movement of the rotary cylinders on said drum, together with bars mounted on the drum carrying the rotary cylinders,

so as to scrape the fibrous stock during its 10 passage between the said bars and the corresponding bars of the apron.

In testimony whereof I have signed my name to this specification.

PAUL EUGÈNE GASTON SWYNGHEDAUW.
